Primary Examiner—Stacia Cadmus(74) *Attorney, Agent, or Firm*—Robert C. Kain, Jr.; Fleit Kain(57) **CLAIM**

The ornamental design for a vehicle seat insert accessory organizer, as shown and described.

DESCRIPTION

FIG. 1 is a front view of a vehicle seat insert accessory organizer.

FIG. 2 is a rear view of the vehicle seat insert accessory organizer.

FIG. 3 is a right side view of the vehicle seat insert accessory organizer.

FIG. 4 is a left side view of the vehicle seat insert accessory organizer.

FIG. 5 is a bottom view of the vehicle seat insert accessory organizer; and,

FIG. 6 is a top view of the vehicle seat insert accessory organizer.

The cross hatched shading shown in FIGS. 1-6 is understood to cover the surface on which it is applied. The dashed lines shown on the vehicle seat insert accessory organizer in FIGS. 1 and 2 are understood to represent stitching.
